UNITED STATES PATENT OFFICE.

SAMUEL E. SPERRY, OF WOODHAVEN, NEW YORK, ASSIGNOR TO INTERTYPE CORPORATION, OF NEW YORK, N. Y., A CORPORATION OF NEW YORK.

SAFETY DEVICE FOR LINE-CASTING MACHINES.

Application filed October 26, 1926. Serial No. 144,272.

This invention relates to typographical machines of the general class disclosed in Letters Patent of the United States, No. 436,532, wherein circulating matrices are leased from a magazine in predetermined order and then composed in a line, the line then transferred into a vertically movable "first elevator" or matrix-supporting member which presents it to the mold, whereupon the mold is filled with molten metal to cast a type-bearing slug against the matrices, and the matrices thereafter returned through a distributing mechanism to the magazine.

In the operation of machines of this character, the composed line of matrices is presented to the mold in accurate and predetermined relation, and if the intended operating relationship or alignment between the mold and the composed matrices is inadvertently or otherwise impaired, then the mold would collide with the matrix-supporting member and damage the machine and cause a faulty delivery or "squirt" of the molten metal.

An object of this invention is to provide means in typographical machines, of the class known under the trade-mark names "Intertype" or "Linotype", for automatically stopping the operation of the machine when the composed line of matrices is improperly aligned, or if there is a misplaced matrix or other extraneous object lodged between the mold and the composed line of matrices or the first elevator.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention, or sacrificing any advantage thereof.

The invention has been illustrated in its preferred embodiment in accompanying drawings, wherein:

Fig. 1 is a fragmentary vertical sectional view taken through a line casting machine, showing the invention applied thereto;

Fig. 2 is a similar view, but depicting another operating phase of the invention;

Fig. 3 is a fragmentary detail view of the usual clutch operating mechanism; 55

Fig. 4 is a perspective view of the invention per se;

Fig. 5 is a fragmentary detail view of the safety device as it is attached to the mold slide; and 60

Fig. 6 is a similar view to Fig. 1, but depicting the safety device as detached from the mold disk.

Referring to the drawings, in which similar numerals refer to similar parts throughout, there is shown the usual main frame 10 in which the mold slide 11 is slidably mounted. The mold disk 12 is journaled to the mold slide, as indicated at 13, and the usual molds 14 are secured to the front or 70 outer face of this disk.

In order that the matrices may be properly aligned with the mold, they are assembled in jaws 15 carried by the first elevator 16, which is mounted for vertical sliding motion. This elevator 16 is positively elevated during the operation of the machine by operating components, not here disclosed, and it descends by force of gravity. The height at which the descent of the first elevator 16 is stopped is determined by the set screw 17 and an alignment stop bar 18, which bar is slidably mounted in the cap 19 of the vise frame 20. Stop pins 21 extend upwardly from the upper face of the bar 18, 85 and when the bar 18 is so positioned that a selected pin 21 is in vertical alignment or registration with the set screw 17, the face of the set screw engages the stop pin 21 and arrests the descent of the first elevator, so 90 that the assembled matrices are positioned in correct alignment for accurate presentation of the mold. This phase of device is well understood in the art and is disclosed in U. S. Letters Patent No. 1,439,586. 95

If the sliding alignment stop bar 18 should be inadvertently set to permit the first elevator 16 to descend to a lower level, and the mold disk were positioned to present a large or so-called "head letter" mold to the 100 matrices, then the mold would collide with the jaw 15 of the first elevator 16, or with the matrices, and thereby damage the machine. In order to obviate the possibility of injury to the machine, in event of the erroneous setting of the alignment stop bar 105

18, or if a misplaced matrix or other object should fall between the mold and the first elevator jaw, or between the mold and matrices, I have provided the following safety 5 means:

The usual hand lever 25 is fulcrumed intermediate its ends to a bracket of the machine by means of a stud 26, and the lower or inner end of the lever 25 is pivotally 10 secured to the upper end of the lever or member 27, which may be termed the "mold slide lever," by means of a pin 28. A roller 29 is operatively secured to the lever 27 intermediate its ends, and this roller is received 15 within the arcuate recess or notch 30 formed in the rear portion of the mold slide 11. There is provided a depending lever or member 31, which may be termed the cam lever, and this lever is fulcrumed to the lever 27 by 20 means of a pin 32 at a point intermediate the upper terminal or lever 27 and the roller 29. A roller 33 is operatively secured to the cam lever 31 at a point intermediate the ends of this lever, which roller is operatively received 25 within the cam groove 34 of the usual mold cam 35. An arm 36 is pivotally secured to the lower end of the lever 27, as indicated at 37, and the lower end of this arm is bifurcated to straddle the pin 38, which is rigidly 30 secured relative to the machine frame. A second arm 41 is pivotally secured to the lower end of the lever 31, as indicated at 42, and extends downwardly to a point immediately adjacent the arm 43 of the usual 35 bell crank lever or clutch operating member 44, which is fulcrumed to the machine frame, as indicated at 45. Another arm 46 of the bell crank 44 cooperates with the collar 47 carried by the clutch shaft 48 to operate the usual machine clutch, which operation is 40 common and well understood by those skilled in the art, and is clearly disclosed in Figure 1 of United States Patent 661,386, granted November 6, 1900, to J. R. Rogers. The 45 arms 36 and 41 are operatively connected, through the instrumentality of a link 50, which link has its opposite ends 51 and 52 pivotally secured to the arms 36 and 41 at points intermediate the terminals of these 50 arms and adjacent their pivotal connections 37 and 42.

The depending lever or member 31 is provided with a transversely-extending recess 53, in which a plunger 54 is slidably mounted. This plunger is pressed by a helical spring 55 into engagement with the lever 27 at a point adjacent the roller 29, thereby normally urging the lever 31 to move about its fulcrum away from the lower portion 60 of the lever 27. The upper or fulcrum portion of the lever 31 is bifurcated to straddle the lever 27, and a stop plate or strap 56 is secured to the front edges of these furcations and cooperate with the lever 27 in a manner 65 to be hereinafter disclosed.

In operation, assuming that a line of matrices is supported in the usual manner by the first elevator in correct position for casting, the rotation of the cam 35 forces the lever 31 forwardly, and since the tension of the 70 spring 55 is in excess of the normal resistance offered by the mold slide, forward movement is imparted to the lever 31 thereby moving the mold slide and mold disk forwardly until the selected mold engages the 75 assembled matrices. During the forward movement of levers 27 and 31 the lower end of the arm 36 is held against movement by the pin 38, and inasmuch as the arm 41 is operatively secured to the arm 36 by means 80 of the link 50, it will work in approximate parallelism with the arm 36 and consequently maintain the lower end of the arm 41 in constant relation to the clutch crank arm 43 during the normal operation of the 85 levers. However, if the first elevator alignment stop bar 18 should be erroneously set, thereby permitting the first elevator to descend to the lower level, as shown in Fig. 2, while the mold disk is positioned to present a "high cap" or "head letter" mold to the matrices, then, as the mold disk moves forwardly, the mold will collide with the rear jaw of the first elevator, as shown. When this occurs the spring 55 will yield 90 and permit the depending lever 31 to move forwardly without imparting further forward movement to the lever 27. As soon as the lever 31 moves forwardly relative to the lever 27 the lower end of the arm 41 moves rearwardly and engages the arm 43 of the bell crank, thereby disengaging the usual clutch members 60 from the cooperating band 61 and stopping the operation of the machine so that no injury is caused to 100 the matrices or to the machine.

Again, if a misplaced matrix or other extraneous object should be inadvertently positioned in the normal path of travel of the mold, or be lodged between the mold and the first elevator or the line of matrices, then the presence of such matrix or extraneous object would check the forward movement of the mold disk before it had reached its normal stopping point and thereby operate the described safety device and effect the stoppage 110 of the machine.

In machines of this character it is frequently desirable to move the mold disk independently of its driving cams or associate mechanism, and in this construction this detachment is brought about by merely moving the handle 25 downwardly, in the usual way, and this downward movement of the handle 25 causes the entire safety device comprising 120 the lever 27, depending lever 31, arms 36 and 41, and link 50 to be raised, thereby withdrawing the roller 29 from its receiving or cooperating recess 30, so that the mold slide may be moved at will independently of 125 130

the lever 27. When the safety device has been detached from the mold slide, as described, the lever 27 is limited in its movement away from the lever 31 by means of the strap 56, and this strap also engages the lever 27 and moves it rearwardly when the cam 34 moves the lever 31 rearwardly.

Having described my invention what I claim is:

1. A typographical machine including means for supporting a composed line of matrices, a mold slide and mold movable to present the mold to the matrices, power driven means for operating the mold slide, clutch operating means, automatically-actuated means operatively interposed between the power driven means and the mold slide for automatically engaging and operating the clutch operating means to stop the operation of the machine when the normal movement of the mold slide is interrupted.

2. A typographical machine including means for supporting a composed line of matrices, a mold slide and mold movable to present the mold to the matrices, power driven means for operating the mold slide, clutch operating means, automatically-actuated safety means detachably secured to the mold slide and operably interposed between the power driven means and the mold slide for automatically disengaging the clutch when the normal movement of the mold slide is interrupted, and means for detaching the safety means from the mold slide.

3. A typographical machine including means for supporting a composed line of matrices, a mold slide and mold movable to present the mold to the matrices, power driven means for operating the mold slide, clutch operating means, and yielding means interposed between the power driven means and the mold slide to automatically disengage the clutch when sufficient resistance is offered to the normal movement of the mold slide to overcome the tension of the yielding means.

4. A typographical machine including a first elevator for supporting a composed line of matrices at different heights relative to the mold, a mold slide and mold movable to present the mold to the matrices, a power driven means for operating the mold slide, and means operatively interposed between the power driven means and the mold slide for automatically stopping the operation of the power driven means when the mold slide is moved into engagement with the first elevator while set at an incorrect height relative to the mold.

5. A typographical machine including means for supporting a composed line of matrices, a mold slide and mold movable to present the mold to the matrices, power driven means for operating the mold slide,

clutch operating means, safety means operatively interposed between the power driven means and the mold slide for automatically engaging the clutch operating means when the normal movement of the mold slide is interrupted, and means for disengaging the safety means from the mold slide to permit independent movement of the mold slide.

6. A typographical machine including means for supporting a composed line of matrices, a mold slide and mold movable to present the mold to the matrices, power driven means for operating the mold slide, clutch operating means, safety means movable with the mold slide and comprising separate components positioned between the power driven means and the mold slide for automatically operating the clutch operating means to stop the machine when the normal movement of the mold slide is interrupted, and means for maintaining the components of the safety means in constant relation to the clutch operating means throughout the normal movement of the mold slide.

7. A typographical machine including means for supporting a composed line of matrices, a mold slide and mold movable to present the mold to the matrices, power driven means for operating the mold slide, clutch operating means, and means operatively interposed between the power driven means and the mold slide and maintained in constant operative relation to the clutch operating means throughout the normal movement of the mold slide to operatively engage the clutch operating means when the normal movement of the mold slide is interrupted.

8. A typographical machine including means for supporting a composed line of matrices, a mold slide and mold movable to present the mold to the matrices, power driven means for operating the mold slide, clutch operating means, safety means operatively interposed between the mold slide and power driven means and including a member which is operatively secured to the mold slide and movable therewith, a depending member operatively secured to the power driven means and movable relative to the first mentioned member, and means operated by the movement of the dependent member relative to the first mentioned member for engaging the clutch operating means to thereby stop the operation of the machine.

9. A typographical machine including means for supporting a composed line of matrices, a mold slide and mold movable to present the mold to the matrices, power driven means for operating the mold slide, clutch operating means, safety means operatively interposed between the power driven means and the mold slide, said safety means including a member which is operatively secured to the mold slide, a depending mem-

ber operatively secured to the power driven means and maintained in fixed relation relative to the first mentioned member during the normal operation of the mold slide and 5 movable relative to the first mentioned member when the normal operation of the mold slide is interrupted, and means operated by the movement of the depending member relative to the first member for operably engaging the clutch operating means.

10. A typographical machine including means for supporting a composed line of matrices, a mold slide and mold movable to present the mold to the matrices, power 15 driven means for operating the mold slide, a clutch operating member, a lever supported adjacent the mold slide and operatively secured thereto, a depending member fulcrumed to the lever and operatively secured 20 to the power driven means and yieldingly held in fixed relation to the lever throughout the normal movement of the mold slide and movable relative to the lever when the normal operation of the mold slide is interrupted, and means operative by the relative 25 movement between the depending member and the lever for operatively engaging the

clutch operating member thereby stopping the operation of the machine.

11. A typographical machine including 30 means for supporting a composed line of matrices, a mold slide and mold movable to present the mold to the matrices, power driven means for operating the mold slide, a clutch operating member, a safety device 35 including a lever operatively supported adjacent the mold slide and operatively attached thereto, a depending lever fulcrumed to the first mentioned lever and operatively secured to the power driven means and yieldingly held in fixed relation to the first lever throughout the normal movement of the mold slide and movable relative to the first mentioned lever when the normal movement of the mold slide is interrupted, and 40 means operative by the said relative movement between the depending lever and the first mentioned lever for operably engaging the clutch operating member thereby stopping 45 the operation of the machine.

50 In testimony whereof I have hereunto set my hand.

SAMUEL E. SPERRY.
